ABSTRACT OF THE DISCLOSURE

A transmit/receive system for semi-electronic teleprinters in which the same groups of components are used for receiving as well as the transmitting, and to supervise the coincidence of a fed-in element with the element actually transmitted over the telegraph line, the system operates as a transmitter during the first half of a signal element and is switched over to operate as a partial receiver during the second half of the signal element to scan the telegraph line.

The present invention relates to a transmitting and receiving system for electronic printing telegraph apparatus which is required for receiving teleprinter signals arriving in series via one telegraph line.

The applicant has already proposed an arrangement which substantially serves the regeneration of teleprinter signals in his application Ser. No. 411,419, filed Nov. 16, 1964, in which the reception and the retransmission of the signals are coupled to one another, and are effected via different lines.

The characteristic feature of this arrangement according to the earlier proposal resides in the fact that the substantial electric component groups serve the reception as well as the retransmission of the teleprinter signals.

The present invention provides a transceiving system for a semi-electronic type of teleprinter which is based on the principle of the double utilization of the substantial electric component groups for both the reception and the retransmission of teleprinter signals. Moreover, the invention provides a semi-electronic teleprinter in which the incoming and the outgoing signals are transmitted on one and the same line at different times and independently of one another. In this teleprinter, according to a further embodiment of the invention, by utilizing the existing component groups, it is determined with the aid of an additional supervisory stage whether the signal (character) printed as the result of depressing a key, actually corresponds to the signal transmitted over the line.

At the reception of teleprinter signals the five signal elements are led in the usual way to five storage flip-flops and, via the setting of five selecting magnets, initiate the printing to be effected by the connected mechanical printing mechanism. The necessary switch-over operations between transmitting and receiving are carried out by a directional stage.

The invention will now be explained in detail with reference to FIGS. 1 to 4 of the accompanying drawings. FIG. 1 shows a schematic block diagram which, for the purpose of providing a better understanding, is restricted to the most substantial features the representation in the block diagrams of FIGS. 1A and 1B show details of the circuitry. The receiving stage of the circuit arrangement comprises the input stage E, the sensing stage A, the receiving trigger ET, the clock-pulse eliminator TA, the clock-pulse generator TG, the series-parallel converter Kz1-Kz5, Dz1-Dz3, and the storages S1-S5. These components correspond in both construction and mode of

2

operation to the receiving system for electronic teleprinters as disclosed by U.S. Patent No. 3,294,908, issued to Werner Schiebeler on Dec. 27, 1966, and to the electronic receiving and transmitting system for teleprinter signals employing a signal generation as described in application Ser. No. 411,419.

The transmitter (sender) of the present circuit arrangement uses most of the same functional groups as the receiving part, viz the timing-pulse eliminator TA, the timing-pulse generator TG, the parallel to serial converter Kz1-Kz5, Dz1-Dz3, and the storages S1-S5. Moreover, the transmitting part includes the keying stage Tst and the output stage Est. In addition thereto, it includes the directional stage RS and the testing stage P which are to be regarded as connecting links between the transmitting and the receiving stage.

The five electromagnets M1-M5 are either energized or not energized by the electronic receiving system via the storages S1 through S5 in accordance with the received teleprinter signals. These five electromagnets, hereinafter referred to as selecting magnets, effect the setting of five code bars of a conventional mechanical printing element to release the type bar associated with the received teleprinter signal combination. The mechanical impact of this type bar is then triggered or released by the sixth electro-magnet M6 which is energized subsequently to the setting or selection of the code bars.

The transmitter keyboard mechanically acts upon the five transmitter contacts ko1 to ko5. By the touch of a finger to the key of a conventional transmitter keyboard

30 the key lever displaces five selector bars which, in turn, effect the setting of the five transmitter contacts ko1 to ko5 in accordance with the pulse or signal combination of the teleprinter signal to be transmitted. Then the transmitting contact is closed when the associated signal pulse is to become a space-mark signal. At the same time, or shortly prior to the setting of the transmitting contacts ko1 to ko5, the tripping contact ko6 is actuated. By this contact ko6 there is initiated the electronic transmission

40 of the teleprinter signal.

If a keyed-in signal is to be transmitted continuously, there must be depression of the continuous key of contact ko7. As long as the contact ko7 is closed, there is effected a continuous transmission of the signal which was the 45 last one to be stored into the circuit arrangement via the transmitting contacts ko1 to ko5. The mode of operation of the circuit arrangement will now be explained in detail with reference to and in connection with FIGS. 1 to 4 of the accompanying drawings, wherein pulse diagram of 50 FIG. 3 shows the various circuit conditions of the most substantial functional blocks.

In the initial position it is assumed that at the last a teleprinter signal was transmitted over the teleprinter line f and that now, after an interval, and via the same line, 55 there is received a teleprinter signal. Prior to this reception a continuous (line) current of 40 ma. flows on the teleprinter line f, which is maintained by a not shown source of voltage (120 volts), and by a series resistance of 3 kilohms. The line current flows through the conducting transistor T26 of the output stage Est, and across the resistor R8. The voltage drop occurring across this resistor keeps the transistor T31 of the input stage E on via the line y2, and keeps the transistor T30 in the off condition. From the collector electrode of transistor T30, 60 and via the line x the receiving trigger ET is maintained in the circuit condition in which the transistor T48 is conducting and in which the transistor T47 is non-conducting.

Upon reception of a teleprinter signal via the teleprinter line (see FIG. 3a) the line current is first of all interrupted by the start element for a period of time of 20 ms. (at 50 bauds). Now the negative voltage at R8 disappears, the transistor T31 is non-conducting, and the transistor

T₃₀ is conducting. The transistor T₄₈ of the receiving trigger ET, however, is now still kept in the conducting state by the discharge current of the capacitor C₃₂. The capacitor C₃₂ is discharged across R₂₂, R₂₁ and the base electrode path of the transistor T₄₈ and via the potentiometer R₂₃. This potentiometer is assumed to be adjusted so that after 10 ms. the discharge of the capacitor C₃₂ has proceeded to such an extent that the receiving trigger ET will be reversed and the transistor T₄₈ is non-conducting, and the transistor T₄₇ is conducting (FIG. 3b). The negative voltage jump at the collector electrode of transistor T₄₈ is conducted via C₃₁, the line v and the diode D₆₁, to the base electrode of transistor C₃₀ of the directional stage RS. Transistor T₃₂ which has previously been assumed as being non-conducting is now conducting (FIG. 3c) and the transistor T₃₃ becomes non-conducting. Via the line z, extending from the collector electrode of transistor T₃₃, as well as via R₂, D₆, and the line i, transistor T₂₄ of the keying stage T_{st} is kept in the conducting condition. Therefore, in the output stage, E_{st} 25 is kept non-conducting, and T₂₆ is kept conducting. In this manner the output stage transistor T₂₆ does not affect the signal reception. Moreover, by the conduction of transistor T₃₂ of the directional stage RS, the line ö becomes currentless so that the transistor T₂₈ of the testing stage P will be non-conducting.

Due to the reversal of the receiving trigger ET, a negative pulse is applied via the line v, R₁₉, and D₇₁, to the base electrode of the transistor T₄₅ of the timing-pulse eliminator TA. This flip-flop reverses and the transistor T₄₅ conducts (FIG. 3d). Then both the clock- or timing-pulse generator TG and the divider Tr will no longer be held off via R₂₄ and R₂₅, and the clock- or timing-pulse generator TG will start to oscillate freely.

With respect to the timing pulse generator TG, a simple type of multivibrator has been shown. However, it is unsuitable for practical application, because the duration of period of its first oscillation does not correspond exactly enough to the duration of period of the following oscillations. Instead of the multivibrator, therefore, it might be advantageous to use a timing-pulse generator TG of the kind as described in the U.S. Patent No. 3,294,908, and in application Ser. No. 411,419, which are also known as sine-wave quartz-crystal, or multivibrator oscillators.

The timing-pulse generator TG starts its oscillations so that the transistor T₄₃ is non-conducting, and the transistor T₄₄ is conducting. Via the capacitor C₃₀ and the line ä a negative pulse is fed to the divider Tr. This divider reverses, in that the transistor T₃₄ is conducting, and the transistor T₃₅ is non-conducting (FIG. 3e). The negative pulse as derived via C₂₄, from the collector electrode of the transistor T₃₅, is fed to the dual counter Dz₁ to Dz₃. This three-stage dual counter forming part of the series-parallel converter has assumed in the hitherto normal condition a position which is referred to as decimal 1 (=stop) in the table shown in FIG. 2. By the first negative stepping pulse via C₂₄, the dual counter Dz₁ to Dz₃ is switched into position 2 (=start) of FIG. 2. (FIG. 3f). Connected to the dual counter Dz₁-Dz₃ are the six coincidence circuits Kz₁-Kz₅ and K_{st}, designed to effect the scanning of six of the seven or eight stable conditions of the dual counter. Via the capacitors C₁₄ to C₂₃, these coincidence circuits effect the erase and the storing into the flip-flops S₁ to S₅ during the signal reception, and effect the forming of the teleprinter signals in the event of transmission.

When the dual counter Dz₁ to Dz₃ has been switched into position 2, there is removed the coincidence at the diodes D₆₄, D₆₅ of the block K_{st}. However, since no coincidence circuit is provided for position 2, no further special processes are being performed at the moment in the circuit arrangement.

The timing-pulse generator TG which, at a telegraph speed of 50 bauds, oscillates at a frequency of 100 c.p.s., supplies after 10 ms. a further stepping pulse to the di-

vider Tr via the line ä. The divider is caused to reverse, so that the transistor T₃₅ will conduct. This process is repeated after 10 ms. The divider Tr is again reversed, and the transistor T₃₅ is non-conducting. A setting pulse is only applied to the dual counter Dz₁ to Dz₃ upon conduction of the transistor T₃₅, so that the counter is switched from position 2 into position 3 (=first element). At points 1 and 2 in the coincidence circuit Kz₁ there is produced a negative voltage (FIG. 3j).

Meanwhile the first "mark"-element or signal pulse has arrived over the telegraph line f (FIG. 3a). Then the transistors T₃₁ and T₂₉ conduct, and the transistor T₃₀ is non-conducting. Both transistors T₂₉ and T₃₀ in block A serve the pulse scanning in that they alternately apply either the line p or the line q to ground or plus potential. In the present case the line q is applied to ground potential. The occurrence of the coincidence event in block Kz₁ now effects one negative pulse each via C₁₄ and C₁₅. However, since the pulse is led behind C₁₅ and via the diode D₂₆ and the line q to ground, the pulse from C₁₄ is applied to the base electrode of transistor T₁₄ of the storage flip-flop S₁. This flip-flop is caused to reverse, the transistor T₁₄ conducts, the lamp L₁ is switched on, and indicates the storing-in of a "mark" pulse (FIG. 3i). In accordance with this storing there is also controlled the selecting magnet M₁. Via the line f there is effected the non-conducting of T₁ and the conducting of T₂, so that now current is allowed to flow through the magnet M₁.

After a period of 20 ms. the dual counter Dz₁ to Dz₂ 30 will receive a further stepping pulse via D₂₄, so that it will be switched into position 4 (=second element) as shown in FIG. 2. The negative voltage at the coincidence circuit Kz₁ will disappear, and will appear instead at the coincidence circuit Kz₂ (FIG. 3k).

Meanwhile, the second "space" element has arrived over the telegraph line f (FIG. 3a). In block A the transistor T₃₀ conducts, and transistor T₂₉ is non-conducting. Accordingly, the line p is applied to ground or plus potential. The negative voltage at points 4 and 3 in block Kz₂ produces negative pulses behind the capacitors C₁₆ and C₁₇, of which the pulse behind the capacitor C₁₆ (and the diode D₃₂) is led via D₃₂ and the line b, to ground. The pulse via C₁₇ is not led off, and is applied to the base electrode of transistor T₁₇ of the second storage flip-flop S₂. Since this flip-flop S₂ was previously assumed as being marked, it is now erased (FIG. 3m), in that T₁₇ conducts, T₁₆ is non-conducting, and the lamp L₂ is switched-off. At the same time, via the line b and via the transistors T₃ and T₄, the selecting magnet M₂ is de-energized. Now, the reception of the second signal element is completed.

The three remaining signal elements are received in an analogous way. Upon reception of the fifth signal element a switching is performed by the dual counter Dz₁ to Dz₂ 55 from position 7 to position 0 (FIG. 2), and transistor T₄₁ of the flip-flop Dz₃ is non-conducting. From the collector electrode of this transistor, and with the aid of C₂₈, a negative pulse is coupled, via the line t and the diode D₆₃, to the base electrode of transistor T₃₇ in the flip-flop Dz₁. Then there is effected the conduction of transistor T₃₇ which was non-conducting prior thereto, and the dual counter Dz₁ to Dz₃ is thus switched from position 0 to position 1. At points 11 and 12 of the coincidence circuit K_{st} there is produced a negative voltage. Via the capacitor C₂₉ this voltage is taken off as a negative pulse and is fed via the line u, to the base electrode of transistor T₄₆ of the timing-pulse eliminator TA. This flip-flop stage TA is reversed, and the transistor T₄₅ is non-conducting (FIG. 3d). Via the resistors R₂₄ and R₂₅ both the timing-pulse generator TG and the divider Tr are prevented from performing further oscillations or reversals, and are switched off, while T₄₃ and T₃₅ are maintained in the conducting state. Accordingly there is completed the reception of a complete teleprinter signal, and if further

teleprinter signals follow, the described processes are repeated.

After an interval, the circuit arrangement is able to transmit a teleprinter signal. Therefore, one of the keys of the transmitter keyboard must be depressed for actuating the contacts k_01 to k_06 , and for selecting or adjusting them in accordance with the necessary pulse combination.

It is assumed that the signal to be transmitted corresponds to the character Y (with the first, third, and fifth elements being "mark" elements). Consequently, the transmitting contacts k_01 , k_03 , k_05 are closed, while the transmitting contacts k_02 and k_04 remain open. Prior to or simultaneously with the actuation of the contacts k_01 , k_03 , and k_05 there is closed the tripping contact k_06 (FIGS. 4, 2). By the closing of this contact k_06 a negative voltage is applied to the line h . Via the capacitor C_3 , C_5 , C_7 , C_9 , C_{11} there is effected the erase of the storage flip-flops S_1 through S_5 . Then the transistors T_{14} , T_{16} , T_{18} , T_{20} , T_{22} are non-conducting, and the lamps L_1 to L_5 are extinguished. The closing of the transmitting contact k_01 effects that a negative pulse will mark the storage flip-flop S_1 via C_4 , in the course of which the transistor T_{14} is unblocked, thus causing the lamp L_1 to be lit. The capacitor C_4 , with respect to the capacitor C_3 , is so dimensioned (for example, double the capacity of C_3) so that the pulse via C_4 will also predominate in cases where the contacts k_06 and k_01 are actuated simultaneously or when the contact k_06 is actuated later. The same applies to the dimensioning of the capacitors C_5 to C_{12} , and to the processes performed during the actuation of the transmitting contacts k_03 to k_05 .

Moreover, upon closing of the tripping contact k_06 , a negative pulse is applied via C_{33} , the line y_1 , the resistor R_{15} and the diode D_{60} , to the directional stage RS , and another negative pulse is applied to the timing-pulse eliminator TA via R_{17} and D_{68} . Both of the flip-flop stages are reversed, in the course of which the transistors T_{33} and T_{45} are made conducting (FIG. 4, d). The directional stage RS , from the non-conducting transistor T_{32} , keeps the transistor T_{28} of the testing stage P in the conducting state via the line $\ddot{o}$. This causes, via the line s_2 , the points 1, 3, 5, 7, 9 in the coincidence circuits Kz_1 to Kz_5 to be connected to chassis ground. For this reason, the latter are first of all rendered inoperative with respect to their influence upon the storage flip-flops S_1 to S_5 . The conduction of T_{33} of the directional stage RS causes the line z to become currentless, so that both the keying stage Tst and the output stage Est are no longer non-conducting.

Subsequently to the reversal of the timing-pulse eliminator TA the timing-pulse generator TG , the divider Tr , and the dual counter Dz_1 to Dz_3 operate in the same way as has already been described hereinbefore with respect to the signal reception. By the first stepping pulse extending from the divider Tr via T_{24} , the dual counter Dz_1 to Dz_3 (FIG. 2) is switched from position 1 (=stop) to position 2 (=start). Then there disappears the negative voltage in block Kst at point 11, the line o is rendered currentless, and the transistor T_{24} of the keying stage Tst is no longer kept in the conducting state via R_7 and $D_{23'}$. The transistor T_{24} is non-conducting, transistor T_{25} is conducting and transistor T_{26} is non-conducting. The line current flowing on the telegraph line is interrupted, and in this way the start element is transmitted. At the same time, in the input stage E and in the scanning block A, the transistors T_{31} and T_{29} are non-conducting, while transistor T_{30} is being made conducting.

After a period of 20 ms. the dual counter is switched in the already described manner to position 3. At point 2 of the coincidence circuit Kz_1 there is produced a negative potential. Point 1, however, will first of all be connected to chassis ground via the conducting transis-

tor T_{28} . Across R_9 , via the line j , R_1 , D_5 , and the line i there will now flow a current to the base electrode of T_{24} of the keying stage Tst . This current is not led off via D_4 in the storage S_1 , because T_{15} has been made non-conducting in consequence of the actuation of the key of the manual keyboard (transmission of the character y). In consequence of the base current the transistor T_{24} is conducting; transistor T_{25} is non-conducting and T_{26} is conducting. Accordingly, a line current will again flow on the telegraph line f , and the first "mark" element will be transmitted. The voltage arising on account of the line current at R_8 in the output stage Est , causes conduction of transistor T_{31} of the input stage E via the line y_2 . The transistor T_{30} is non-conducting, and transistor T_{29} is conducting. Accordingly the line q is applied to chassis ground, whereas the line p is applied to negative potential.

10 ms. after the beginning of the first signal element the divider Tr is again reversed by a stepping pulse on line $\ddot{a}$ (FIG. 4a), in the course of which the transistor T_{35} is conducting. Via the line s_1 and the capacitor C_{13} , a positive pulse is taken off the collector electrode of the conducting transistor T_{35} , and is applied to the base electrode of the transistor T_{28} of the test stage P . The transistor T_{28} is temporarily non-conducting (FIG. 4k) and is then kept in the conducting state via the line $\ddot{o}$. A negative voltage will become temporarily effective at point 1 of the coincidence circuit Kz_1 . Via the capacitors C_{14} and C_{15} this voltage causes negative pulses. Behind C_{15} , however, the pulse is redirected via T_{26} and the line q , towards chassis ground, because the transistor T_{29} is conducting. The pulse via C_{14} , however, is applied to the base electrode of transistor T_{14} of the storage device S_1 . There, however, the pulse is ineffective because the transistor T_{14} is already conducting. Accordingly, the circuit condition of the flip-flop S_1 is not changed.

20 ms. later the transmission of the first signal element is completed. The dual counter effects the switching from position 3 to position 4 (FIG. 2). At point 4 of the coincidence circuit Kz_2 there is produced a negative voltage. The current resulting therefrom via R_{10} and the line k_3 , however, is redirected via D_9 and the conducting transistor T_{17} of the storage flip-flop S_2 , towards chassis ground. The line i is thus rendered currentless, so that transistor T_{24} of the keying stage Tst will become non-conducting. Likewise there is no conduction of the transistor T_{26} of the output stage Est and interruption of the line current. The second signal element becomes a "space" element. At r_8 there is effected no voltage drop, thus causing the non-conduction of transistor T_{31} of the input stage E . In block A, transistor T_{30} is conducting, and transistor T_{29} is non-conducting. On account of this the line q is applied to -12 volts, and line b is applied to chassis ground.

55 If, 10 ms. later, the transistor T_{28} in the test stage P is temporarily non-conducting by a positive pulse arriving over C_{13} and D_{24} , as has been described in analogy with respect to the first signal element, then the negative pulse arriving over C_{16} , is redirected via D_{32} and line p to chassis ground; the pulse arriving over C_{17} (both in block Kz_2), however, is applied to the base electrode of transistor T_{17} in the storage flip-flop S_2 . This flip-flop is not affected, because transistor T_{17} was already conducting prior thereto. After another 10 ms. the transmission of the second signal element is completed.

60 The dual counter returns to position (FIG. 2), and with respect to the block Kz_3 there are met the coincidence requirements, so that a negative voltage will appear at point 6. The transmission of the third signal element which is supposed to become a "mark" element, is now initiated. Since in this case, transistor T_{19} in the storage S_3 is non-conducting, the current flowing across R_{11} and via the line 13 , is re-directed towards chassis ground via D_{13} . In fact, it continues to flow via R_4 , D_{14} , and the line i to the base electrode of transistor T_{24} of

the keying stage T_{st} . Transistor T_{24} is conducting, transistor T_{25} is non-conducting and transistor T_{26} is conducting.

Let us now assume that the transmission of this third "mark" element is being disturbed or prevented by a failure of some sort or other, for example, if the telegraph line f is temporarily interrupted, so that no line current is flowing through T_{26} and R_8 . In this case the transistor T_{31} of the input stage T_{st} will not be conducting via the line y_2 . Then, transistor T_{30} conducts and transistor T_{29} is not conducting. The line p is applied to chassis ground, and the line q is applied to -12 volts. After 10 ms. the transistor T_{28} of the test stage T is temporarily non-conducting as described before. As a result of this a negative needle pulse will occur at point 5 of the coincidence circuit K_{z3} . This pulse which is transferred via C_{18} and the line l_1 , is re-directed to chassis ground via T_{39} and the line p . The pulse via C_{19} and the line 12, however, is applied to the base electrode of transistor T_{19} in the storage flip-flop S_3 . The transistor T_{19} conducts and, consequently, the flip-flop is reversed. It now assumes a different position than the one which was imprinted upon it at the beginning of the actuation of the transmitting contacts k_{o1} to k_{o6} . The result of this will be, that after the effected, and as was assumed, faulty transmission of the teleprinter signal upon controlling of the printing tripping stage AA , a different character than the one originally depressed on the keyboard will be printed in accordance with the present invention.

After another 10 ms. hence altogether 80 ms. after the beginning of the signal transmission, there is completed the transmission of the third signal element (see FIG. 4). The dual counter switches from position 5 to position 6 (FIG. 2). At point 8 of the coincidence circuit K_{z4} there is produced a negative voltage, and the transmission of the fourth signal element is initiated. The transmission of the fifth signal element is effected in the same way as has been described hereinbefore with respect to the first three signal elements.

Subsequently to the transmission of the fifth signal element the dual counter is reset from position 7, via position 0, to position 1 (FIGS. 2, 4e and f). At point 11 of the coincidence circuit K_{st} there occurs a negative voltage which, via the line o and i , causes the transistor T_{24} of the keying stage T_{st} to conduct and, consequently, also the transistor T_{26} of the output stage Est , so that on the telegraph line f there will be flowing the line current of the stop element. Moreover, via the line r and the capacitor C_1 , there is started the univibrator $T_{11}-T_{12}$ of the printing tripping stage AA . This univibrator is reversed, and for the time duration of its reversal, the transistors T_{11} and T_{13} are conducting, and the magnet M_6 for the printing of the character, is energized. Together with the energization of the selecting magnets M_1 to M_5 , this causes the printing of the character which has been transmitted by the output stage Est , and which has been checked by the input stage E and the scanning (or sensing) stage A .

Due to the negative voltage existing at points 11 and 12 of the coincidence circuit K_{st} , the flip-flop TA of the timing-pulse eliminator is reversed via C_{29} , the line u , and the diode D_{70} , so that the timing-pulse generator TG ceases to oscillate. The whole system has completed one cycle, and has re-assumed its normal position.

As in the transmission of a single character there is also effected the continuous transmission of a character (letter). To accomplish this, the continuous-transmission key k_{o7} in addition to the block K_{st} will have to be depressed. As long as this continuous-transmission key is depressed the character which was the last one to be stored into the storage flip-flop S_1 to S_5 , will be permanently transmitted with 1.5 times the stop element. The processes deviating from what has been described hitherto, are as follows: By depressing the continuous transmission key k_{o7} , the transistor T_{42} in block K_{st} is

non-conducting. The negative voltage occurring at its collector electrode will serve to cause conduction of the transistor T_{45} of the timing-pulse eliminator TA via the line b , R_{18} , and D_{69} , and will keep this transistor in the conducting condition as long as the contact of key k_{o7} is closed. The flip-flop TA is reversed, and the timing pulse generator TG starts to oscillate, so that now the signal transmission commences. The further processes are then performed as described hereinbefore with respect to the transmission of individual signals. Upon reaching the stop, however, the position 0 of the dual counter D_{z1} to D_{z3} will not be skipped (see FIG. 2) because the negative pulse otherwise effecting this skipping, is now re-directed via C_{28} and by the diode D_{67} , to point 12 which is grounded via k_{o7} . The flip-flop D_{z1} accordingly, is not reset via the line t , but maintains its just assumed position for a period of 10 ms. The negative pulse as taken from the collector electrode of transistor T_{41} via C_{27} , however, will remain unaffected, and still serves to reverse the divider Tr via D_{62} . This pulse is responsible for effecting that the divider Tr will transmit a new stepping pulse after 10 ms., so that in this way there can be produced half a signal element of 10 ms.

A switching-off of the system via the line u and the flip-flop TA does not take place because point 12 is connected to chassis ground via the continuous-transmission key k_{o7} , and is thus prevented from receiving a negative voltage. Only after the opening of k_{o7} and after the coincidence requirement has been met in the block K_{st} , is the negative voltage occurring at point 12 capable of reversing the flip-flop TA of the timing-pulse eliminator via the capacitor C_{29} and the line u , thus resetting the system to normal.

It should be mentioned that this inventive type of circuit arrangement is in no way restricted to use in semi-electronic teleprinters only, but that it may be used quite generally. In particular it is not necessary to actuate mechanical contacts for effecting the transmission of a character (letter) instead, it is possible to connect the amplifiers outputs of a photoelectric tape reading analyser. Likewise, for effecting the printing of a character or letter there is no need for connecting the selecting magnets because it is also possible to use electronic decoding devices for this purpose.

What is claimed is:

1. An electronic circuit arrangement for effecting reception and transmission of teleprinter signals comprising: a series-to-parallel converter including coincidence stages and a dual counter; a clock-pulse generator serving as a time base; a directional stage which determines the direction of intelligence flow; a frequency divider which steps-on said converter by dividing the frequency of the pulse generator; associated storages which are coupled to the coincidence stages; a source of incoming signals; a receiving trigger which in response to the incoming signal changes the directional stage into a position predetermined for the signal reception, and which triggers a clock pulse eliminator for starting both the clock-pulse generator and frequency divider; and said coincidence stages, in the receiving state and in rhythm with the incoming signal elements, transmit pulses which mark the respective storage or couple the pulse to ground, said coincidence stages transmit in addition a keying pulse which, depending on the assumed position of the associated storage, controls a transmitter keying stage or its coupled to ground, and said directional stage is controlled by the respective operating condition such that an incoming start element switches it into the receive position and the actuation of a transmitter tripping contact switches it into the transmit position.

2. An arrangement according to claim 1, including transmitting contacts which are actuated to effect direct marking of said storages and actuation of said tripping contact.

3. An arrangement according to claim 1 in which: said directional stage when in the receiving position causes said keying stage to be non-conducting, and said directional stage when in the transmitting position causes a testing stage, which is coupled between the directional stage and the coincidence stages, to couple the storage marker lines to ground.

4. An arrangement according to claim 3, wherein said test stage, in the middle of each keying pulse, is temporarily rendered ineffective by the clock-pulse generator, and that during the time it is ineffective, marking pulses are applied to said storages in accordance with the potential momentarily prevailing on the incoming line.

5. An arrangement according to claim 1, in which said coincidence stages successively transmit two parallel pulses, and depending on the potential prevailing on the teleprinter line, one of said two pulses marks the associated storage and the other pulse is coupled to ground via a sensing stage.

6. An arrangement according to claim 5, including another coincidence stage coupled to the dual counter and adapted so that the coincidence established by the stop element of each signal causes said keying stage to return

to a normal condition, and said other coincidence stage suppresses said clock-pulse generator and effects the tripping of a printing mechanism.

5 7. An arrangement according to claim 6, wherein one output from said other coincidence stage triggers a univibrator which effects the tripping of the printing mechanism.

10 8. An arrangement according to claim 6, wherein said other coincidence stage is switched, by the actuation of a repeat key, from its normal position to position which release the clock-pulse generator, and said dual counter is stepped-on so that the timing adhered to is one and a half times the length of the stop element.

15 9. An arrangement according to claim 2, including electronic input devices, the outputs of which are connected to said associated storages.
